CLAIM

The ornamental design for a strap with hook and loop closure for a cord management system, as shown and described.

DESCRIPTION

The present application relates to the following Patents and Applications:

to U.S. utility patent application Ser. No. 12/761,326, filed Apr. 15, 2010, (now abandoned),
to U.S. design patent application Ser. No. 29/368,746, filed Aug. 27, 2010 (now U.S. Pat. No. D636,659),
to U.S. design patent application Ser. No. 29/368,755, filed Aug. 27, 2010, (now U.S. Pat. No. D667,291),
to U.S. design application Ser. No. 29/388,372, filed Mar. 28, 2011, (now U.S. Pat. No. D645,333),
to U.S. design application Ser. No. 29/401,643, filed Sept. 13, 2011,
to U.S. design application Ser. No. 29/401,359, filed Sept. 11, 2011, and
to U.S. design application Ser. No. 29/401,360, filed Sept. 11, 2011.

FIG. 1 is a perspective view of our new design of a strap with hook and loop closure for a cord management system;

FIG. 2 is a top view of FIG. 1;

FIG. 3 is a bottom view of FIG. 1;

FIG. 4 is a view of a first side of FIG. 1;

FIG. 5 is a view of a second side of FIG. 1;

FIG. 6 is a view of a third side of FIG. 1;

FIG. 7 is a view of a fourth side of FIG. 1;

FIG. 8 is a perspective of FIG. 1 shown in an alternate configuration of use with an object; and,

FIG. 9 is perspective view of FIG. 1 shown in another alternate configuration of use with an object.

The broken lines represent environment and form no part of the claim.
